CLAIM

The ornamental design for a manifold base for electromagnetic valve, as shown and described.

DESCRIPTION

FIG. 1 is a front, top, and left side perspective view of a manifold base for electromagnetic valve;

FIG. 2 is a rear, bottom, and right side perspective view thereof;

FIG. 3 is a front elevational view thereof;

FIG. 4 is a rear elevational view thereof;

FIG. 5 is atop plan view thereof;

FIG. 6 is a bottom plan view thereof; and,

FIG. 7 is a left side elevational view thereof, the right side elevational view being a mirror image of the left side elevational view shown.

The broken lines shown in the figures are for the purpose of illustrating portions of the manifold base for electromagnetic valve that form no part of the claimed design.
